LOCOMOTIVE TENDER WITH OIL SEPARATOR

Filed Oct. 10, 1925

UNITED STATES PATENT OFFICE.

THOMAS F. JACKSON, OF WINNIPEG, MANITOBA, CANADA, ASSIGNOR TO THE SUPER-HEATER COMPANY, OF NEW YORK, N. Y.

LOCOMOTIVE TENDER WITH OIL SEPARATOR.

Application filed October 10, 1925, Serial No. 61,866, and in Canada January 11, 1928.

My invention relates to locomotive tenders and has particular reference to the purification of water returned thereto from a locomotive feedwater heater.

In cases where the feed water of a locomotive is heated by means of an exhaust steam heater of the closed type, a considerable quantity of the exhaust steam is condensed in the heater and must be disposed of, the quantity of condensate being too great to be discharged into the locomotive stack or to the ground. For this reason, and also because of the desirability of conserving the locomotive water supply, the condensate is ordinarily returned from the heater to the locomotive tender.

The return of the heater condensate directly to the tender is objectionable, however, because of the lubricating oil which is carried from the engine cylinders by the exhaust steam into the heater condensate, and it has been found desirable to provide filters in the condensate return line so that only pure water is returned to the tender. Exhaust steam heaters are generally located so that the condensate is returned to the tender by gravity, but the elevation of the heater above the top of the tender tank cannot exceed a very small amount, and for this reason any filter which imposes any appreciable resistance on the flow through the condensate return line is unsuitable for use in this connection.

It is the object of my invention, therefore, to provide a filter or oil separator which will effectively remove any oil in the heater condensate before it is returned to the tender tank, and which will, at the same time, impose no resistance on the flow through the condensate return line. It is a further object of the invention to produce a separator of this character which may be readily and cheaply installed in existing tender tanks and which will be unaffected in operation by variations in the level of the water in the tank. Further and more detailed objects of the invention will become apparent in connection with the following description of a preferred embodiment of the invention, illustrated in the accompanying drawings, in which Figure 1 is a fragmentary vertical section of a tender tank showing the separator installed therein; Figure 2 is a plan view of the inte-

rior of a portion of the apparatus shown in Figure 1, and Figure 3 is an end view of the valve controlling the separator discharge line.

Referring now to Figure 1, the tender tank is indicated generally at 1, having the usual bottom sheet 2, top sheet 3, and filling opening 4 with hinged cover plate 5. Sheet 6 separates the tank from the coal space 7 of the tender.

The main body of the separator is formed by the cylindrical casing 8 extending downwardly through an aperture in the top sheet 3 of the tank and resting upon the bottom sheet 2. At its lower end the casing 8 is closed by the sheet 9, having an aperture therein communicating with a drain pipe 10, which extends through the bottom sheet 2 and is controlled by valve 11. The casing 8 is extended above the level of the sheet 3 through an opening therein and is suitably secured to the sheet, as by means of the angle iron 12. Preferably the casing 8 should extend slightly above the level of the top of the filling opening 4 for a reason which will become apparent later, although extension to this height is not essential. A cover plate 13 is provided for the casing 8, having an opening therein through which communication is established between the top of the casing and the top of the tender tank by means of a pipe connection 14, connecting this opening with a similar opening in the sheet 3.

Communication between the main tank 1 and the lower portion of the casing 8 is established by means of a pipe 15, which extends upwardly from a point inside the casing near the bottom thereof and terminates in an elbow 16, secured to the casing around an opening therein slightly below the level of the top of the main tank 1. The condensate return pipe 17 enters the casing through the upper portion thereof and terminates in an extension 18, having a discharge opening near the bottom level of the tank. An overflow pipe 19 is provided having an inlet inside the casing approximately at the level of the top of the main tank 1 and is controlled by a valve 20, the weighted operating arm 21 of which is connected to the hinged cover plate 5 by means of chain 23, so that when the cover plate is opened the valve is thrown to

open position. When the cover plate 5 is closed the valve 20 is held in closed position by the weighted operating arm 21. A baffle 22, is provided within the casing 8 dividing 5 the lower portion thereof into two compartments. The extension of the condensate discharge pipe extends into one of these compartments, while the pipe 15 forming the communication between the casing and the main 10 tank 1 extends into the second compartment.

The operation of the device is as follows: When the tender tank is filled, water flows into the casing 8 through pipe 15 until the levels in the main tank and in the casing are 15 the same, pipe 14 providing means for the equalization of air pressures. Condensate discharged from pipe 18 is forced to flow upwardly through one of the lower compartments in the casing by the baffle 22 and any 20 oil contained in the condensate rises to the top of the water in the casing 8. The continued discharge of condensate into the casing 8 tends to raise the water level therein above the level in the tank 1, and the cover plate 5 25 and valve 20 being closed, this causes an overflow through pipe 15 into tank 1. As water is withdrawn from the main tank 1, and the water level therein drops, the water level in the casing 8 will correspondingly be 30 lowered until it reaches the level of the opening at 16. As this is the lowest opening in the casing 8, the minimum water level in the casing will be at this point, regardless of the water level in the tank 1, so that oil separated 35 from the condensate and floating in the casing 8 is always kept a considerable distance above the inlet of pipe 15, which discharges only oil free water into the main tender tank.

When the main tank is filled the valve 20 in 40 the overflow pipe is first automatically opened by the opening of the filling cover 5, and as such tanks are invariably filled until they overflow, the water level is carried upward into the filling opening 4. This raises the 45 water level in the casing 8 to a point above the inlet of the overflow pipe 19, which serves to discharge the water from the top of the casing, together with the accumulated oil floating thereon. It will thus be seen that 50 the water level within the casing 8 can vary only between two discharge openings, regardless of water conditions within the main tank, while the condensate passing through the casing 8 is forced to travel a tortuous path 55 of considerable length, and as the cross sectional area at this point is comparatively large, a low rate of flow results, which gives ample opportunity for the oil in the condensate to separate and rise to the top of the 60 water in the casing, from which point it is periodically removed through the overflow 19 as the tank is filled.

I claim:

1. In apparatus of the class described, the

combination with a locomotive tender tank, of 65 a closed casing extending downwardly therein, a pipe establishing communication between the lower portion of said casing and the upper portion of said tank, a condensate discharge pipe opening into said casing at a 70 point remote from the inlet end of said first named pipe, and an overflow pipe leading from the upper portion of said casing.

2. In apparatus of the class described, the combination with a locomotive tender tank, 75 of a closed casing extending downwardly therein, a pipe having an inlet end adjacent to the bottom of said casing and an outlet end near the top of said tank, a condensate discharge pipe opening into said casing adjacent to the bottom thereof, a baffle dividing the lower portion of said casing into two compartments, said baffle extending from the bottom upwardly between said pipes to a point substantially above the lower ends thereof, 80 and an overflow pipe leading from the upper portion of said casing.

3. In apparatus of the class described, the combination with a locomotive tender tank having a filling opening and cover therefor, of 90 a casing extending downwardly into said tank, a pipe establishing communication between the lower portion of said casing and the upper portion of said tank, a condensate discharge pipe opening into said casing, an overflow pipe leading from the upper portion of said casing, a valve controlling said overflow pipe, and a mechanical connection between said cover plate and said valve for opening and closing the latter with the former. 95

4. In apparatus of the class described, the combination with a locomotive tender tank having an opening in the top thereof, of a closed casing extending from a point above the top of said tank through said opening to the bottom of the tank, a condensate return pipe opening into said casing adjacent to the bottom thereof, an overflow pipe having an inlet substantially at the level of the top of said tank and leading from said casing, a pipe having an opening adjacent to the bottom of said casing and extending upwardly to an opening communicating with said tank, and a baffle located between said first named and said last named pipes, said baffle extending from the bottom of said casing substantially to the top of said last named pipe. 110

5. In apparatus of the class described, the combination with a locomotive tender tank having an opening in the top sheet thereof, a filling opening and a cover plate therefor, of a casing extending from a point above said tank through said first named opening substantially to the bottom of the tank, a condensate return pipe having a discharge opening in said casing adjacent to the bottom thereof, a second pipe providing communication between the lower portion of said casing 115 120 125

and the upper portion of said tank, a baffle located between the discharge end of said condensate pipe and the inlet end of said second named pipe, a pipe providing communication between the top of said tank and the top of said casing, an overflow pipe leading from said casing and having an inlet sub-

stantially on a level with the top of said tank, a valve controlling said overflow pipe, and a mechanical connection between said valve and 10 said cover plate for opening and closing the former with the latter.

THOMAS F. JACKSON.
